DESIGN FOR A COMBINED LAPEL PIN AND PERFUME CONTAINER

Harold Graeter, Sherman, Conn., assignor to Cartier, Inc., New York, N. Y., a corporation of New York

Application October 9, 1945, Serial No. 122,682

Term of patent 14 years

(Cl. D45—19)

To all whom it may concern:

Be it known that I, Harold Graeter, a citizen of the United States of America, residing at Sherman, in the county of Fairfield and State of Connecticut, have invented a new, original, and ornamental Design for a Combined Lapel Pin and Perfume Container, of which the following is a specification, reference being had to the accompanying drawing, forming part thereof.

I claim:

The ornamental design for a combined lapel pin and perfume container, as shown.

HAROLD GRAETER.
